Des. 206,061
Patented Oct. 25, 1966

206,061

PICKET

Albert H. Magness, Emmorton Road, Bel Air, Md.

Filed Oct. 23, 1965, Ser. No. 87,839

Term of patent 14 years

(Cl. D13—7)

FIG. 1   FIG. 2

FIGURE 1 is a side elevational view of a picket showing my new design.

FIGURE 2 is a side elevational view of an adjacent side of the picket.

FIGURE 3 is a sectional view taken on line 3—3 of FIGURE 2.

FIGURE 4 is an enlarged fragmentary perspective view of the picket.

I claim:

The ornamental design for a picket, as shown.
